HOT TOP FOR INGOT MOLDS

Application filed October 10, 1929. Serial No. 398,594.

This invention relates to hot tops, and constitutes a continuation in part of our application Serial No. 316,140, filed October 31st, 1928.

It is well known in the art that a hot top consists of a hollow refractory body which is fitted over an ingot-mold to contain a volume of molten metal (after the ingot has been teemed) above that which comprises the ingot in the ingot-mold proper. This upper body of metal flows downwardly and fills the so-called pipes which form within the ingot as it cools.

According to usual practice a portion of the hot top extends into the bore of the ingot-mold a slight distance downwardly past its upper edge. This serves to prevent molten metal from escaping between the ingot-mold and the hot top. In operation, it is this portion of the hot top which is destroyed. That is to say, the metal of the ingot engages this portion of the hot top, and in contracting during cooling tends to fracture it. The remainder of the hot top above this downwardly extending portion is relatively substantial.

We propose to provide a hot top formed of several refractory members, which may be adequately assembled in position on an ingot-mold to serve in the desired manner. That is, we do not form the downwardly extending portion of the hot top integral with the remainder of the hot top, as has been the practice heretofore. Obviously, the lower portion of the hot top may be renewed each time that an ingot is cast, and the upper portion of the hot top may be used repeatedly.

To prevent molten metal from entering the joint between the two hot top portions and forming a lateral fin on the sinkhead, we provide a thin metal lining. It is with parted hot tops of this nature, and with means to protect the joint between the several portions of an assembled hot top that our invention has to do.

In the accompanying drawings Figure I is a central vertical sectional view, indicating fragmentarily an ingot-mold, and showing the hot top of our invention operatively associated therewith; Figure II is an eleva-

tion showing in plan the top of an ingot mold which has a fluted bore; Figure III is an elevation showing in bottom plan the lower portion or member of the hot top; Figure IV is an elevation in plan showing the assembled hot top mounted on the ingot-mold; and Figure V is a view in section taken on the plane V—V of Figure I.

Referring to the drawings, the reference numeral 1 indicates an ingot-mold having the bore 2. Figure I illustrates generally a hot top, embodying the features of our invention, positioned on the mold. The hot top comprises an upper refractory body 3, and a lower refractory member 4. A portion 4a of the member 4 extends into the bore of the mold, and it fits snugly to prevent molten metal, as in teeming the mold and hot top are filled, from escaping at the top 5 of the mold. Obviously, the portion 4a must be shaped to conform with the bore of the ingot-mold. As the member 4 is not integral with the other portions of the hot top, the upper member 3 thereof may be of an unspecialized form (for instance, it may be of circular section or form, as shown in the drawings) regardless of the sectional contour of the bore of the ingot-mold and of the lower member.

The upper member seats on an appropriate surface 6 on the lower member 4. To prevent molten metal from entering at this surface between the members 3 and 4, we provide a thin metal lining member 7, which is retained suitably within the two hot top portions. Through-pins 8 serve adequately to retain the lining member. In addition to protecting the line of jointure between the two hot top portions, the metal lining member prevents the molten metal from coming into direct contact with the refractory material of the top. This is desirable because it minimizes the tendency of the hot top to spall, and to drop fragments into the steel.

We have shown the hot top resting immediately on the upper edge 5 of the ingot mold, but it is to be understood that the assembled hot top may be blocked up in the manner known to the art. This is a well known practice, and no illustrations is deemed

to be necessary; suffice it to say, that our top is adaptable to this practice.

What we claim is:

1. A hot-top for ingot molds comprising
5 an outer portion of refractory material, said
outer portion being formed of an upper and
lower member, the lower member having a
depending portion outwardly contoured to
fit the inner surface of the ingot mold, and
10 a thin metal lining member arranged with-
in the two refractory members aforesaid.

2. A hot-top for ingot molds comprising
an outer portion of refractory material, said
outer portion being formed of an upper and
15 a lower member, the lower member having a
depending flange with its outer surface con-
toured to fit the inner surface of the ingot
mold, the inner surface of said flange being
of a section to correspond and align with the
20 inner surface of said upper member, and a
lining member removably arranged within
the said refractory members.

In testimony whereof we have hereunto set
our hands.

25 EUGENE L. MESSLER.
JAMES THOMAS.
